AERIAL HOISTING AND HAULING APPARATUS OF THE FORM COMMONLY KNOWN AS CANYON SKIDDERS

Application filed October 4, 1927. Serial No. 223,957.

Our invention relates to improvements in aerial hoisting and hauling apparatus of the form commonly known as "Canyon skidders," which apparatus embodies a main track cable, a carriage movable thereon, and a plurality of operating or control cables for moving the carriage and hoisting and hauling loads.

The apparatus hereinafter described is designed for use in connection with logging operations in canyons or deep ravines where long and heavy cables are required to drop down from a suspended carriage to a load that is to be picked up or moved, but it will be understood that said apparatus may be employed in all other industries where similar conditions prevail.

The object of our invention is to provide simple and efficient means for controlling the lowering of that portion of a cable or skidding line known as the tong line, which tong line runs over a sheave or drum in the carriage and may extend downwardly therefrom for a comparatively long distance to the load that is to be hoisted or moved.

More specifically stated, the object of our invention is to provide means for lowering or overhauling the tong line by establishing a driving connection between the carriage sheave or drum over which said tong line passes and another line embodied in the apparatus and known as the slack pulling line, and which is used for slackening the tong line or drawing the same back toward the carriage.

In hauling and loading apparatus of this type, heretofore used, and which does not embody our invention, it has been found to be impossible to get a long tong line to run back over the carriage sheave or drums without attaching needless weight to the end of said tong line. It has also been found that a short tong line or a longer tong line that is weighted will not always run back at a constant velocity but will sometimes hang

in the air for a while and then drop down rapidly, thus endangering workmen below. Our present invention overcomes both of these difficulties by providing means for winding the tong line down at a constant velocity.

A further object of our invention is to provide a predetermined length of tong line with respect to the slack pulling line and to positively maintain, in spite of stresses developed during operation, said predetermined length of tong line until it is desired to make a change in the length of the tong line. That is, it is our purpose to maintain a set registration of the tong line, skidding line and slack pulling line relative to each other.

A still further object of our invention is to have the slack line sheave disposed above and in spaced relation to the slack line drum and at the same time have the said drum positively actuated by the said sheave. Such arrangement prevents entanglement of the tong line with the slack line, the tong line being peculiarly subject to many twists while handling the load, and, being of heavy steel cable construction, such twisting is transmitted throughout a considerable portion of the length of the line and is a cause of considerable loss of time by reason of its entangling with other lines, unless the two are maintained in spaced relation.

Other and more specific objects of the invention will be apparent from the following description taken in connection with the accompanying drawings:

In the drawings, Figure 1 is a view in side elevation, with parts shown in dotted lines, of a carriage constructed in accordance with our invention;

Fig. 2 is an edge view of the same;

Fig. 3 is a side elevation, on a smaller scale, showing the carriage and the cables in connection with which it is operated;

Fig. 4 is a somewhat diagrammatic eleva-

tion on line 4—4 of Fig. 3 showing the manner of winding the cables about the carriage sheaves or drums;

5 Figs. 5 and 6 illustrate one modified form of the invention;

6 Figs. 7 and 8 show a further modified form of the invention;

7 Figs. 9 and 10 show another modified form of the invention;

10 Figs. 11 and 12 show still another modified form of the invention;

11 Figs. 13 is an elevation showing still another modified form of the invention.

12 Like reference numerals designate like parts throughout the several views.

13 In our disclosure, embodied herein, the apparatus is all old and well known except the driving connection between the slack pulling line and the tong line drum.

14 Figs. 1 to 4 inclusive show a carriage formed of two spaced apart side plates 13 having two track sheaves 14 and 15 rotatively mounted between their upper ends and adapted to run on a track cable 16 that may be anchored at both ends to form a suspended trackway. Two slack pulling line sheaves 17 and 18 are rotatively mounted on opposite sides of the carriage and are arranged to have a slack pulling line so selectively passed

20 over either of said pulleys as may be desired. The slack pulling sheaves 17 and 18 are preferably both rigidly secured on the same axle 21 which is rotatable in the carriage frame and which has a sprocket wheel 22 also rigidly secured thereon. An endless sprocket chain, or link belt, 23 passes around the sprocket wheel 22 and around another sprocket wheel 24 which is secured to a sheave or drum 25 hereinafter designated as a tong

30 line drum. An axle shaft 26 is provided for the sprocket wheel 24 and tong line drum 25. A tong line or cable 27 operates over the tong line drum 25 one end dropping downwardly therefrom and the other end extending horizontally and forming a part of a skidding line 28 that may extend to a suitable power operated winding drum, not shown. A slide-40

45 able swivel 29, known as a Shay swivel, is provided on the skidding line and arranged to engage with a stop 30 on said line. The cable designated as the tong line 27 is, in reality the end portion of the skidding line back as far as the stop 30, or that portion of the skidding line which is adapted to run over

50 the tong line drum 25 and hang downwardly. The lower end of the tong line is adapted to have choker lines 31, or other means for engaging a load, connected therewith.

55 The slack pulling line 20 is connected with the Shay swivel 29 on the skidding line 28, thence passes around one of the sheaves 17 or 18 and thence back substantially parallel to the skidding line to a suitable source of power, as a winding drum, not shown, by which it may be hauled in.

60 The skidding and tong line 28—27 is for lifting and hauling in the load. The track cable supports the weight of the carriage and load. An outhaul line 32 draws the carriage out after a load has been hauled in and the slack pulling line 20 is used to draw the skidding line back so that the tong line 27 may run down over the tong line drum 25 after the carriage has been drawn back to a point above which the load is to be picked up. The necessary weight of choker lines 31 and other apparatus on the end of the tong line 27 will draw down a short tong line when the slack pulling line is pulled in and the swivel 29 moved toward the carriage, it being apparent that the lower end of the tong line will be drawn up close to the carriage when the carriage is drawn out after a load has been released. If a long tong line is used then this weight will not be sufficient and the tong line will sag between the swivel 29 and the carriage in an obvious manner. In logging equipment we find that the maximum length of tong line that can be made to run back by gravity without the use of excess weights will not exceed two hundred feet, whereas in some of such logging operations a tong line of eight hundred to one thousand feet in length is required.

65 In accordance with our invention, the slack pulling line, which is ordinarily used for pulling the skidding line toward the carriage and thereby slackening the tong line, is, in our invention, further used for positively winding down or lowering the tong line by positively actuating the tong line drum. In this wise, a tong line of any required length can be caused positively to run over the tong line drum and be thereby lowered at any desired speed. By reason of the positive actuation of the tong line drum, it is possible to keep the tong line taut so as to prevent it from sagging, kinking and entangling. Further, by reason of such positive actuation of the tong line drum it is possible to prevent the tong line from being lowered rapidly or suddenly dropping with consequent danger to the workmen. Finally, this positive control or actuation of the tong line drum provides for the elimination of all unnecessary counterweight on the end of the tong line, thereby enabling the workmen the more readily to drag the end of the tong line into the woods to make connection with the logs.

70 In the carriage shown in Figs. 1 to 4 inclusive, the tong line drum 25 is driven by the link belt 23 when the slack pulling line is wound in, all of the parts moving in the direction shown by the arrows in Fig. 4.

75 In the adaptation shown in Figs. 5 and 6 the slack pulling line passes from the Shay swivel over a slack pulling line sheave 33, thence downwardly around a sheave 34 which is rigid with the tong line drum thence back up and around the sheave 33 and thence out

wardly to the means, not shown, by which it may be wound in. When the slack pulling line is wound in the tong line drum will be rotated and the tong line lowered, the various parts moving in the directions indicated by the arrows in Fig. 5.

In Figs. 6 and 7 the slack pulling line is shown as passing from the Shay swivel over a slack pulling line sheave 35 thence down and around a driving sheave 36 that is rigid with the tong line drum, thence directly out to the means, not shown, by which it is wound in, whereby it will rotate the tong line drum and wind the tong line down when the slack pulling line is wound in.

In Figs. 9 and 10, the slack pulling line passes from the Shay swivel over a sheave 37 thence down and around a driving sheave 38, which is connected with the tong line drum, thence up over an idler sheave 39, and thence outwardly to its source of power, thereby affording means for driving the tong line drum and controlling the lowering the tong line.

In Figs. 11 and 12 we show a modified form 25 of carriage in which the tong line drum 40 and the driving drums or sheaves 41 therefor are located in a separate block 42 that is flexibly connected by means 43 with a main carriage body 44. In this device the slack pulling line extends from the Shay swivel, over a sheave 45 in the carriage 44, thence downwardly past an idler sheave 46, thence around the driving sheave 41, thence upwardly over another idler sheave 47 in the 35 main carriage 44 and thence outwardly to its source of power.

In Fig. 13 we show a carriage in which the tong line drum 48 is driven by a train of gears 49, 50 and 51 that connect with the slack pulling line sheave 52.

In some instances wide sheaves or drums are shown and the cables wrapped one or more times around the same to secure the necessary traction for driving. In other instances sheaves with convergent or V shaped peripheral grooves are shown for frictionally gripping and driving the cables, the two forms being generally interchangeable as desired.

In all of the forms of the invention disclosed the slack pulling cable is used to positively drive the tong line drum or sheave and control the lowering of the tong line.

In all of the embodiments herein disclosed the slack pulling line sheaves are provided on both sides of the carriage so that the slack pulling line may be on either side.

Obviously, changes may be made in the forms, dimensions, and arrangement of the parts of our invention, without departing from the principle thereof, the above setting forth only a preferred form of embodiment.

We claim:

1. Apparatus of the class described embodying a tong line drum supported for ro-

tation, a tong line arranged to run over said tong line drum and extend downwardly therefrom, a skidding line connected with the tong line, a slack pulling line directly and integrally connected with the skidding line for pulling the skidding line toward the drum, and sheave means operated by the slack pulling line for rotating the tong line drum. 70

2. In apparatus of the class described, a track cable, a carriage movable on the track cable, a tong line drum supported for rotation by said carriage, a skidding line, a tong line connected with the end of said skidding line, and arranged to run over said tong line drum and extend downwardly 75 80 therefrom, a slack pulling line directly and integrally connected with the skidding line and tong line, a sheave in the carriage for the slack pulling line to pass over, and sheave means operated by the slack pulling line for 85 rotating the tong line drum.

3. In apparatus of the class described, a track cable, a carriage movable thereon, a tong line sheave rotatable in the carriage, a tong line arranged to run over said sheave, 90 a skidding line connected with the tong line, a slack pulling line sheave rotatable in the carriage, a slack pulling line passing over said sheave and connected with the skidding line at the junction of said skidding line and said tong line, a sprocket wheel connected with said slack pulling line sheave, another sprocket wheel connected with said tong line drum and a sprocket chain connecting said two sprocket wheels, whereby positive driving 95 means is provided for said tong line sheave. 100

4. An apparatus of the class described embodying a carriage having a tong line drum and a slack line sheave in spaced relation, said sheave being located above said drum; a skidding line; a slack pulling line operatively disposed over said slack line sheave, said slack pulling line being directly secured to said skidding line at a desired point in spaced 105 relation to the end of said skidding line, thereby providing a tong line of predetermined length formed from said skidding line as a direct continuation of said skidding line, the said tong line being operatively disposed over the tong line drum; a sprocket wheel operatively mounted on said slack line sheave; a second sprocket member operatively mounted on said tong line drum; and a sprocket chain operatively disposed over 110 said sprocket members. 115

5. An apparatus of the class described embodying a carriage having a tong line drum and a slack line sheave; a skidding line; a slack pulling line operatively disposed over said slack line sheave, said slack pulling line being directly secured to said skidding line at a desired point in spaced relation to the end of said skidding line, thereby providing 120 125 a tong line of predetermined length formed 130

from said skidding line as a direct continuation of said skidding line, the said tong line being operatively disposed over the tong line drum; and positive driving means operatively connecting said slack line sheave to said tong line drum, whereby a definite predetermined tong line length and a positive actuating means for said tong line is provided.

In witness whereof we hereunto subscribe our names this 26th day of September, A. D. 1927.

JAMES M. MEANY.
JOSEPH H. DICKINSON.
